LUMINAIRE HOUSING

Richard B. Glickman, Sherman Oaks, and George R. Hartz, Canoga Park, Calif., assignors to Berkey/Color Tran Mfg., Inc., Burbank, Calif.

Filed Sept. 26, 1969, Ser. No. 19,317

Term of patent 14 years

Int. Cl. D26—02

U.S. Cl. D48—20

FIG. 1.

FIG. 2.

FIG. 3.

FIG. 4.

FIG. 5.

FIG. 6.

FIG. 1 is a top plan view of a luminaire housing incorporating our new design.

FIG. 2 is a front elevational view thereof.

FIGS. 3 and 4 are opposite side elevational views thereof.

FIG. 5 is a rear elevational view thereof.

FIG. 6 is a bottom plan view thereof.

We claim:

The ornamental design for a luminaire housing, substantially as shown.
